LINE-CARRYING ROCKET

Conrad David Schermuly, Alfred James Schermuly, and Charles Schermuly, Parkgate, Newdigate, England

Application October 30, 1947, Serial No. 783,023
In Great Britain October 30, 1946

5 Claims. (Cl. 102—89)

1

This invention relates to line-carrying rockets and has for its object to provide a rocket capable of carrying a heavier line and/or capable of traveling for a greater distance than hitherto.

It has already been proposed to provide a rocket casing having two charges of propellant composition separated by delay means, so that after the first charge has been burned away, the second charge is ignited after a delay. Such rockets have the drawback that the course of the rocket during the burning of the second charge is determined by the orientation of the rocket at the time when the second charge commences to burn. Since during the delay between the exhaustion of the first charge and the commencement of burning of the second charge, the rocket may commence to fall, the direction of flight during the burning of the second charge may be downwards and in any case is likely to be other than during the burning of the first charge. This renders the whole flight inaccurate.

According to this invention a rocket comprises a front casing and a rear casing, the said casings being capable of relative axial displacement and both containing a propellant composition, and means for ensuring ignition of the two propellant compositions at substantially the same time.

When the rocket is to be fired from a discharger by means of a cartridge, the means for ensuring ignition of the two propellant compositions at substantially the same time may consist of a passage throughout the length of the rear casing so that the flash from the cartridge not only ignites the propellant composition in the rear casing but also passes through the said passage and ignites the propellant composition in the front casing.

Alternatively, a fuze may be led from the rear end of the propellant composition in each of the casings, the free ends of the fuses being joined together so that they may be ignited simultaneously.

Any suitable means may be provided to ensure the required axial displacement. For example, one casing may carry one or more rods projecting from the end thereof and passing through corresponding sleeves secured to the other casing, the rods being provided with stops to limit the relative axial movement. Alternatively one casing may be somewhat wider than the other so that the smaller casing may slide within the end of the larger casing, the portion of the larger casing within which the smaller casing slides being apertured to allow the escape of the combustion products from the propellant charge in the larger casing when the rocket is in flight.

2

The propellant composition may be of the kind which is provided with a central hollow around which ignition takes place so that the composition burns outwardly, or it may be of the kind in which the composition is spaced inwardly from the casing and is ignited on its outer surface so that it burns inwardly. The invention will now be described with reference to the accompanying drawings in which:

10 Figure 1 is a side elevation of one embodiment of rocket according to this invention,

Figure 2 is a side elevation of the embodiment of Figure 1 in flight position,

Figure 3 is a plan view of the rocket of Figure 2,

Figures 4 to 6 are views similar to Figures 1 to 3 but of a second embodiment of the invention,

Figures 7 and 8 are enlarged views of the front and rear portions of the rocket of Figure 2, the lower half being in section, and

Figure 9 is an enlarged view of parts of the rocket of Figure 6, the lower half being in section.

Referring first to Figures 1 to 3, a front rocket casing 1 has secured to its rear end a collar 2 to which are secured two sleeves 3 into which are secured rods 4. Slidable on the rods 4 are two sleeves 5 secured to a collar 6 which is secured to the forward end of the rear rocket casing 7. Movement of the rear casing 7 in a rearward direction is limited by stops 8 welded or otherwise secured to the ends of the rods 4. The collar 6 has secured thereto two further sleeves 9, into which are secured two rods 10 to the free ends of which is hinged a bridle 11 for the attachment of a line to the rocket.

The construction is shown in greater detail in Figures 7 and 8. The casing 1 is closed at the front end by a plug 12 and a layer of clay 13, and contains propellant composition 14 having a tapered hollow 15 at its rear end, and also an annular layer of clay 16 and a choke 17. The rear casing 7 is provided at its front end with a plug 18 the front of which is of frusto-conical shape and is adapted to project into the rear end of the casing 1 when the two casings are in the position shown in Figure 1. The rear casing 7 also contains a clay plug 19, propellant composition 20 having a tapered hollow 21, an annular layer of clay 22 and a choke 23. A central passage 24 is formed through the plugs 18 and 19 and through the propellant composition 20. This passage 24, with the tapered hollow 21 and the apertures in the layer of clay 22 and in the choke 23 provide an opportunity for the flash from a cartridge ignited behind the end of the rear cas-

ing 7 to pass right through the centre of the casing 7 and ignite the composition 14 in the front casing 1.

In operation, the bridle 11 is swung into the position shown in Figure 1 and the rear casing 7 is inserted into the barrel of a discharger containing a cartridge. The front end of the barrel abuts against the collar 6 and the rods 4 and 10 are situated outside the barrel. When the cartridge is fired, the flash ignites both the propellant compositions 14 and 20 and the rocket assumes in flight the position shown in Figures 2 and 3.

Referring now to Figures 4, 5, 6 and 9, the rear casing 25 is of less diameter than, and slides within, the front casing 26. The rear portion of the front casing 26 is provided with apertures 27 to permit the escape of gas.

After the rear casing has been inserted into the front casing, two plates 28 are secured to the casing 25 by means of screws one of which is shown at 29 in Figure 9. When the casing 25 moves rearwardly within the casing 26, the rearward movement is limited by the plates 28 striking against the rear edge of the apertures 27 within which they are situated (as shown in Figures 5, 6 and 9).

To each of the plates 28 there is welded a sleeve 30 in which is fixed a rod 31. A bridle 32 is hinged to the rear ends of the rods 31.

The contents of the casings 26 and 25 may be the same as those of the casings 1 and 7 in Figures 7 and 8. Alternatively, and as shown in Figure 9, the propellant composition 33 and 34 may be in the form of pressed cylinders which are held in spaced relationship to the casings 26 and 25 by means of spiders 35. The ignition of the propellant composition 33 and 34 may be by means of fuzes and in order to indicate the way in which these fuzes may be arranged they are shown in Figure 9, although in actual fact when the rocket is in the flight position shown in Figure 9 the fuzes will have burned away. One fuze 36 is joined at its front end to the composition 33 in the front casing 26, passes through a bore in the plug 37 which closes the front end of the casing 25, passes through the space between the composition 34 and the casing 25 and out through the choke 38 where it is joined to another fuze 39 which is attached to the composition 34.

In operation the fuzes 36 and 39 are ignited while the casings 25 and 26 are in the position shown in Figure 4. As soon as the compositions 33 and 34 commence to burn, the rocket takes flight and assumes the position shown in Figures 5, 6 and 9.

If desired, the fuzes 36 and 39 may be omitted and the rocket shown in Figure 9 fired by means of a cartridge. The flash from the cartridge not only ignites the composition 34 but also passes through the space between the composition 34 and the casing 25 and through the bore in the plug 37 (a plurality of these bores preferably being provided in this case) and ignites the composition 33.

In cases where the casings 25 and 26 are provided with outwardly burning propellant composition (similar to that described with reference to Figures 1 to 3, 7 and 8), the rocket in the position shown in Figure 4 may also be fired from a discharger by means of a cartridge.

The simultaneous burning of the two propellant compositions results in the rocket having greater speed and pull than in the case of a rocket of the same size but containing only one propellant composition. Consequently it is possible to use heavier lines than have hitherto been possible with a given weight of rocket.

We claim:

1. A rocket comprising a front casing and a rear casing, means on the front casing supporting the rear casing for limited axial sliding movement relative to the front casing, two rods secured to the rear casing, a bridle hinged to said rods, a propellant composition in each of said casings and means for ensuring ignition of the two propellant compositions at substantially the same time.

2. A rocket comprising a front casing and a rear casing, means on the front casing supporting the rear casing for limited axial sliding movement within the rear portion of the front casing, apertures in said rear portion of the front casing for the escape of gas, two rods secured to the rear casing within two of the apertures in the front casing, said rods being spaced from said front casing to permit the insertion of the rear portion of said front casing in a discharger, a propellant composition in each of said casings and means for ensuring ignition of the two propellant compositions at substantially the same time.

3. A rocket as claimed in claim 1 wherein said rods are spaced from the rear casing to permit the insertion of said casing in a discharger.

4. A rocket as claimed in claim 2 wherein said two rods are secured to said casing within two of the apertures in the front casing and said rods are spaced from said front casing to permit the insertion of the rear portion of said front casing in a discharger.

5. A rocket comprising a front casing and a rear casing, means on the front casing supporting the rear casing for limited axial sliding movement relative to the front casing, a bridle secured to the rear casing for the attachment of a line, a propellant composition in each of said casings and means for ensuring ignition of the two propellant compositions at substantially the same time.
